UNITED STATES PATENT OFFICE.

ALBERT HOYT TAYLOR, OF GRAND FORKS, NORTH DAKOTA, AND LEO C. YOUNG, OF VAN WERT, OHIO.

METHOD OF RECEIVING RADIOSIGNALS WITH THE COMPOUND HETERODYNE.

1,414,232.

Specification of Letters Patent. Patented Apr. 25, 1922.

Application filed August 12, 1919. Serial No. 317,066.

To all whom it may concern:

Be it known that we, ALBERT HOYT TAYLOR, and LEO C. YOUNG, citizens of the United States, and residents, respectively, of Grand Forks, in the county of Grand Forks, and State of North Dakota, and Van Wert, in the county of Van Wert and State of Ohio, have invented an Improvement in Methods of Receiving Radiosignals with the Compound Heterodyne, of which the following is a specification.

The object of this invention is to provide a method of reception, especially adapted to continuous waves, which has a much higher degree of selectivity than either audion or heterodyne reception, and which is sufficiently simple in manipulation to be capable of immediate practical application in high power and other radio work.

The increased selectivity is obtained by the use of a tuned intermediate circuit placed between the ordinary receiving or detecting apparatus and secondary detector, combined with the use of a heterodyne or oscillating circuit whose frequency is so chosen that it combines first with the signal to produce an intermediate frequency and second with the intermediate frequency to produce audible response.

The present invention differentiates radically from the electric circuits disclosed in the prior art in that it is characterized by a single heterodyne which reacts on the incoming wave to produce an intermediate frequency and which intermediate frequency is acted upon a second time by the same heterodyne after having passed through an intermediate tuning circuit. This compound, or successive operation of the same heterodyne results finally in the production of an audio frequency which is intensified through several stages of amplification and then actuates a signal responsive device. The reaction of the single heterodyne can be repeated several times in the circuit if desired, there being, theoretically, no limit in the number of stages in the compounding action.

Our invention has been illustrated diagrammatically in the accompanying drawing in which A is the antenna which is tuned in the usual manner by means of the variable primary P and variable primary condenser C₁, and coupled in the usual manner to a secondary receiving circuit tuned by the condenser C₂ and variable secondary inductance S. Either a crystal detector or bulb may be used with this secondary circuit, which will be called the primary detector. The drawing shows a three element bulb employed in the usual manner as a primary detector D₁. Magnetically coupled to the secondary S is an oscillating circuit H, containing variable condenser C which is capable of variation over a range of at least double that of the wave lengths to be received. Any arrangement of oscillating bulb may be used for H which is capable of giving the required range of wave lengths. If the frequency of the incoming signal as received in the secondary S is f₁ and the frequency of the heterodyne is f₂ then there will be set up in the output circuit of the detecting apparatus D₁ a current of frequency f₃ = f₁ minus f₂, which is amplified by a two stage amplifier A₁ and A₂ especially designed for the range of intermediate frequencies to be handled.

The output circuit of the last amplifier is tuned by means of the variable condenser C₃ and inductance P' to the frequency f₃ and is loosely coupled to the secondary S', which is tuned by means of the condenser C₄ and connected in the usual manner with the secondary detector D₂. A certain amount of the frequency f₂ passes by way of the secondary circuit S and the amplifiers A₁ and A₂ and the intermediate loose coupled circuit P' and S' to the detector D₂ and here combines with the frequency f₃ to give an audible signal whose frequency f₄ is equal to f₃ minus f₂. The output circuit of D₂ passes to a two stage audio frequency amplifier, A₃—A₄, which may or may not be necessary, according to the type of receiving collector which is used. The

output circuit of A, is connected to signal responsive device T associated with a tuned circuit comprising the variable condenser C_5 and inductance L_5 . The circuit is applicable to any known type of receiving collectors, that is to say to loops, antennæ, ground wires, sea wires or balanced systems.

The action of the circuit may be illustrated for a wave length of 15,000 meters. 10 f_1 equals 20,000, f_2 equals 10,600, f_3 equals 9,400 cycles and the final audible signal equals f_2 minus f_3 equals 1,200 cycles. The circuit is called the compound heterodyne as one heterodyne is made to function two 15 or more times, once on the detector D_1 and its accompanying circuits and then on detectors D_2 , D_3 , etc. The result of the first action is to produce an intermediate frequency, which can be sharply tuned by the 20 intermediate tuning condensers C_3 and C_4 and inductance P' and S' . The intermediate frequency is usually inaudible when ordinary telephones are used for reception, and when ordinary ranges of wave lengths 25 are handled. If it should be desirable to apply the circuit to an extremely long wave, say 30,000 meters, the intermediate frequency could be audible, were it not for the use of the absorbing circuit consisting of the 30 inductance L_5 , and capacity C_5 , which circuit is placed in parallel with the telephone receivers and tuned to the intermediate frequency f_3 , thereby effectually preventing this frequency from penetrating the telephones. Under ordinary conditions the circuit L_5 and C_5 is not necessary.

The superior selectivity of the circuit may be demonstrated from the following figures. Taking the same illustration as previously, 40 suppose the circuit is set according to the figures given above for a 15,000 meter wave, that is a frequency of 20,000 per second. If now an interfering wave is produced differing by 2%, it will have a frequency f_1 equals 45 20,400 or 19,600. Let the first case be taken as an illustration. If the adjustments of the set are left correct for 15,000 meters, the interfering wave will have an intermediate frequency of 9,800, so that this interfering 50 wave and intermediate frequency will be 4% out of tune. Furthermore, on account of the extremely loose coupling possible in the intermediate circuit, the selectivity is greatly enhanced. It will be noted that the heterodyne frequency must be close to one half the wave frequency.

The operation of the set in practice is as follows: The primary and secondary having been previously calibrated are set, with 60 a moderately loose coupling, for the wave to be received. The intermediate circuit having been previously calibrated, is set with a fairly tight coupling for a wave length ap-

proximately twice as long as the wave to be received. The amplifiers are adjusted in the usual manner, it being only necessary to burn the bulbs at normal brilliancy. The heterodyne H is then adjusted in frequency by means of its rotary variable condenser C_1 , until the signal is heard, after which the coupling of the intermediate circuit is loosened and slight adjustments of the tuning condensers C_3 and C_4 are made, if necessary. If then the intermediate frequency should be audible in the telephones as an extremely high pitched note, it is removed by adjusting the tuning condenser C_5 . For waves up to 15,000 meters this last is, however, not necessary.

The following observations taken on signals from Nauen, Germany, show the high selectivity of the system. An artificial signal was produced so as to have an audibility estimated between 20,000 and 30,000, and differing only 1% from Nauen's wave, 12,600 85 meters. This interfering signal was received on the compound heterodyne receiving set with an audibility of 40 at the same time that Nauen's signals had an audibility of 200. The same experiment was 90 made with an ordinary autodyne receiving set, using a very loose coupling, and gave an audibility of 50 for the interfering signal and 15 for Nauen's signal. In other words, 95 the new circuit, according to the audibility measurements, cleared the interference between fifteen and twenty times better than the standard autodyne circuit. It would have been an easy matter to have continued perfect copy on Nauen's signals with a high 100 power American station transmitting at the same time on a wave length differing from Nauen's by only 100 meters, whereas this could not have been done with the ordinary autodyne circuit.

The frequency for the heterodyne is very easily determined from the equation

$$f_2 = \frac{f_1 \pm f_4}{2}$$

and that the intermediate frequency f_3 then becomes

$$f_3 = \frac{f_1 \mp f_4}{2}$$

If it is desirable to get a still higher degree of selectivity it is possible to make the same heterodyne act a third time on the circuit by the introduction of a third detecting bulb D_2 and a second intermediate circuit. The 120 relationship will then be as follows and the frequency f_4 will not be within the ordinary range of audibility, but will be heterodyned again by the frequency f_2 and passed through another intermediate tuned circuit, detected 125 by a third detector and finally received as

an audible frequency f_5 . The heterodyne frequency is then determined by the relation:

$$f_2 = \frac{f_1 \pm f_5}{3}$$

5 and there will be two intermediate frequencies. Then

$$f_3 = \frac{2f_1 \mp f_5}{3}$$

10 which is the first intermediate frequency. The second intermediate frequency:

$$f_4 = \frac{f_1 \mp 2f_5}{3}$$

15 To illustrate again at 15,000 meters, that is, if f_1 equals 20,000, if the heterodyne be set at 6,333, f_3 will be equal to 13,666, which will be the frequency of the first intermediate circuit and f_4 will equal 7,333, which is the frequency of the second intermediate circuit, and 1,000 will be equal to the frequency of the final audible signal. Now, this process may, theoretically, be carried on indefinitely leading to a higher and higher degree of selectivity, and on account of the way the amplifiers can be used, that is to say on the intermediate frequencies, there will be no loss of signal, but rather a gain of signal.

20 30 It is evident that if the number of intermediate circuits which it is decided to use is N , then the number of heterodyne actions which are obtained with the one heterodyne is $N+1$, and if the final frequency of the 35 audible signal be f , the frequency of the heterodyne will be

$$f_2 = \frac{f_1 \pm f}{N+1}$$

40 In practice it has been found that sufficient selectivity can be obtained without using more than two intermediate circuits.

Having thus described our invention what we claim is:

45 1. The method of selectively receiving radiosignals which consists in combining the incoming oscillations with locally generated oscillations to produce a resultant beat current, rectifying said beat current, combining such rectified beat current with the aforesaid locally generated oscillations to produce a second beat current, and observing the effect of said second beat current.

50 2. The method of selectively receiving undamped radiosignals which consists in combining the incoming oscillations with locally generated oscillations to produce a resultant beat current, and combining the resultant beat current with the same locally generated oscillations to produce a second beat current of frequency sufficiently low to be observed by a signal responsive device.

60 3. The method of selectively receiving

radiosignals which consists in combining the incoming oscillations with locally generated oscillations to produce a resultant beat current, rectifying and amplifying said beat current, combining such rectified and amplified beat current with the aforesaid locally generated oscillations to produce a second beat current, and observing the effects of said second beat current.

65 4. The method of selectively receiving radiosignals which consists in combining the incoming oscillations with locally generated oscillations, the frequency difference of such oscillations being such as to produce a beat current of frequency above audibility, rectifying the said inaudible beat current, combining it with the same locally generated oscillations to produce a second beat current of audible frequency, and causing said second beat current to actuate a signal responsive device.

70 5. The method of selectively receiving radiosignals which consists in combining the incoming oscillations with locally generated oscillations to produce a resultant beat current, passing said resultant beat current through a circuit, resonating said circuit to the beat frequency, combining the beat current with the same locally generated oscillations to produce a second beat current, and observing the effects of said second beat current.

75 6. The method of selectively receiving radiosignals which consists in combining the incoming oscillations with locally generated oscillations to produce a resultant beat current, passing said resultant beat current through a circuit, materially detuning said circuit from the incoming oscillations, combining said resultant beat current with the same locally generated oscillations to produce a second beat current, and observing the effects of the second beat current.

80 7. The method of selectively receiving radiosignals which consists in combining the incoming oscillations with locally generated oscillations of frequency chosen to produce a beat current of frequency differing from the frequency of the locally generated oscillations only by an amount within the audible range, passing said locally generated oscillations and said beat current through a circuit, approximately tuning said circuit to the frequencies of both, combining the locally generated oscillations with the beat current to produce a second beat current, and observing the effects of the second beat current.

85 8. The method of selectively receiving radiosignals which consists in combining the incoming oscillations with locally generated oscillations to produce a resultant beat current, combining the resultant beat current,

with the same locally generated oscillations to produce a second beat current, continuing this operation until a beat current of the desired characteristics is produced, and observing the effects of said last beat current.

9. The method of selectively receiving radiosignal oscillations which consists in causing a single source of locally generated oscillations to act a plurality of times on a single received signal to produce a plurality of beat currents, and observing the effects of one of said beat currents.

10. The method of selectively receiving radiosignal oscillations which consists in causing a single source of locally generated oscillations to act a plurality of times on a

single received signal to produce a plurality of beat currents, selectively amplifying one or more of said beat currents, and observing the effects of one of said beat currents.

20

11. The method of selectively receiving radiosignal oscillations which consists in causing the same local source of oscillations to act a plurality of times on a single received signal to produce a plurality of beat currents of different frequencies, observing the effects of one of said beat currents, and selectively absorbing disturbing currents.

In testimony whereof, we have affixed our signatures this 26th day of July, 1919.

ALBERT HOYT TAYLOR.
LEO C. YOUNG.
